DESIGN FOR A COMBINED CHANGE TRAY AND GUMMED TAPE HOLDER

Jacob Jonik, Detroit, Mich.

Application January 25, 1938, Serial No. 74,521

Term of patent 3½ years

To all whom it may concern:

Be it known that I, Jacob Jonik, a citizen of the United States and a resident of 5109 Harold Street, in the city of Detroit, county of Wayne, and State of Michigan, have invented a new, original, and ornamental Design for a Combined Change Tray and Gummed Tape Holder, of which the following is a specification, reference being had to the accompanying drawing, forming part thereof.

Fig. 1 is a top plan view of a combined change tray and gummed tape holder, showing my new design.

Fig. 2 is a side elevation thereof.

Fig. 3 is a front view thereof.

I claim:

The ornamental design for a combined change tray and gummed tape holder, as shown.

JACOB JONIK.
